UNITED STATES PATENT OFFICE

CHARLES A. GRAHAM, OF EAST CLEVELAND, OHIO

DESIGN FOR A GAME BOARD

Application filed February 15, 1932. Serial No. 42,879. Term of patent 7 years.

To all whom it may concern:

Be it known that I, CHARLES A. GRAHAM, a citizen of the United States, residing at 1734 Chapman Avenue, in the city of East Cleveland, county of Cuyahoga, and State of Ohio, have invented a new, original, and ornamental Design for Game Board, of which the following is a specification, reference being had to the accompanying drawings, forming part thereof.

Figure 1 is a plan view of a game board, showing my new design. Figure 2 is a cross-sectional view taken along the line 2—2 of Figure 1.

I claim:

The ornamental design for a game board, as shown.

CHARLES A. GRAHAM.
